SWITCH CONTROLLING DEVICE

Leonard T. Jenkins, Chicago, Ill.

Application March 13, 1930, Serial No. 435,462

6 Claims. (Cl. 200—35)

My invention relates to means for the making and breaking of an electric circuit, and has for its principal object the provision of a device adapted for association with an electric socket switch whereby the switch mechanism of the socket may be controlled and timed by connecting the device to the alarm stem or shaft of a clock.

The device may find a ready use in connection with machines or appliances where it may be found necessary to control the operation of the same at predetermined periods. In another instance, the alarm hand of the clock may be set at a certain time for controlling the turning on or off of a number of electric lights in the display windows of business establishments. The device may further be used in starting an electric motor which may in turn regulate the functioning of an oil burning furnace or stove at certain periods of the day.

Another object of my invention is to provide a switch controlling element which may be quickly attached to an electric socket switch, and which is adapted for movement therearound in certain positions to thereby permit either the switch controlling element to operate the switch for turning the same on or off, or allow one to manually operate the switch when said controlling element is in a neutral position.

A further object of my invention is the provision of a switch controlling element which may be constructed for detachable association or connection with socket switches of various types.

A still further object of my invention is the production of a device that is simple in construction, of a small number of parts, easily manufactured, economical as to cost, and durable and efficient for its intended purpose.

Many other objects and advantages of my invention will be evident after reading the disclosure hereinafter set forth in conjunction with the drawing forming a part hereof.

With this end in view, my invention consists in the novel construction, arrangement and combination of parts herein shown in which,

Fig. 1 is a view in elevation showing my device associated with a clock;

Fig. 2 is an enlarged sectional view taken substantially on the line 2—2 of Fig. 1, showing only the switch controlling element in section and also a portion of the clock casing and the alarm shaft;

Fig. 3 is a section taken substantially on the line 3—3 of Fig. 2;

Fig. 4 is a modified construction showing cam means for controlling the switch means of a socket; and

Fig. 5 is a view in elevation illustrating means whereby it is possible to detachably associate the switch controlling element with a socket switch.

With reference to the drawing, wherein the elements or parts comprising my device are shown, letter A indicates generally a common type of electric socket switch, composed of a body part 1 and a head 2, with switch mechanism means arranged therein, with the plunger means 3 of the switch mechanism extending in a transverse position relative the longitudinal axis of the electric socket switch. Letter B indicates a cord which is secured to a source of current, and letter C indicates a line and plug adapted for association with the socket. Although a particular type of socket switch is shown, it is to be understood that any of the various types of common sockets in commercial use may be satisfactorily used, providing they have received the approval of the Underwriters Laboratories. By slight alterations of the switch controlling element the same may be adapted for controlling any of the various types of switch mechanism means which are arranged in the various types of switches. Rotatably mounted upon the enlargement of the head 2 of the socket is a band 4 with its edges 4' partially enclosing the enlargement to prevent the band from becoming loose. Secured by any suitable means as by welding, soldering, or the like, to the band 4 is a support 5, which in the present case, comprises the lower section or portion of a socket body part 1. The support 5 of course may be constructed in various other forms to accomplish its intended purpose. The support 5 is provided with openings 6 through which the plunger means of the switch mechanism rides when the band 4 and support 5 are rotated about the longitudinal axis of the socket. While in this embodiment the support 5 is shown secured to the annular band 4, it is to be understood that it may be secured to a suitable band which is constructed and arranged for rotation relative the body part 1 of the socket, or if desired, two bands may be used for securing the support, one of which may be rotatable on the head of the socket and one on the body part of same. Rotatably or movably mounted in the support 5 transversely of the longitudinal axis of the socket is a bent shaft 7 having a bent portion 8, and rotatably mounted on the bent portion 8 of the shaft is a roller 9 adapted for contact with the plunger means 3 of the switch mechanism means of the socket.

It will be evident that the shaft 7 is provided to have its ends extend in certain positions so that the female end 10 of the shaft is a trifle longer than the end 11 of the shaft. In many alarm clocks the alarm winding stem to which the key is adapted to be attached does not extend exteriorly of the casing of the clock D and therefore, it will be evident why I have provided the female end 10 of the shaft 7 of a relatively long length, as this will enable the device to be posi-

- tioned a sufficient distance from the back of the clock D to thereby prevent the device from interfering with the other controlling mechanisms projecting from the back of the clock.
- 5 The female portion 10 of the shaft is shown extending through the opening 12 provided in the back 13 of the clock, in threadable engagement with the male portion 14 of the alarm clock shaft or stem 15.
- 10 It will thus be apparent that to attach the device to the alarm shaft or stem 15 of the clock D the key 16 is removed from the male portion 14 of the alarm stem 15 and applied to the male portion 17 adjacent the end 11 of the shaft 7.
- 15 The device is then applied to the shaft or stem 15 of the clock D by attaching the female portion 10 of the stem 7 to the male part 14 of the alarm clock shaft 15 by turning the key 16 in the direction necessary for winding the alarm mechanism of the clock. After this operation of winding the alarm spring has been completed, the timing mechanism of the clock may be set at a certain time to rotate the alarm shaft or stem 15 of the clock which will in turn set in motion 20 the shaft 7 in a direction to cause the roller 9 one the bent portion 8 of the shaft 7 to contact with the plunger means of the switch mechanism, it being understood, of course, that the plunger means has been previously brought into 25 the desired position opposite the roller 9. To prevent extreme wear upon the support 5 by reason of rotation of the shaft 7, suitable bearings such as 18 may be arranged adjacent the inside of the support 5 in any suitable manner. It is 30 also to be understood that the shaft 7 may be provided with means whereby the same may be adjusted in positions to and from the longitudinal axis of the socket switch, the object of which would permit one to use the switch controlling 35 attachment on other types of sockets other than that which is shown, and which will also allow the shaft 7 to be adjusted to compensate for any variation in the distances that the ends of the plunger means extend from the socket switch. 40 Obviously, the energy exerted by the agency of the alarm spring of the clock is sufficient to overcome the resistance offered by the spring of the switch mechanism of the socket switch to thereby turn the switch on or off. It will also be 45 evident from the operation of the device that the switch controlling element does not interfere or prevent the alarm from continually ringing after the switch mechanism of the socket switch has performed its operation of making or breaking 50 of the circuit.
- 55 Fig. 4 is a view substantially the same as that set forth in Fig. 3, clearly showing a modified switch controlling means which consists principally of a cam 20 affixed to a straight shaft 21, the shaft 21 being mounted in a support 22 similar to the support 5.
- In Fig. 5, I have clearly shown a band means 23 which is formed with arms 24 through which extends a bolt and nut means 25 whereby it is 60 possible for one to detachably associate the switch controlling element with various types of socket switches.
- Having thus described my invention, it is obvious that various immaterial modifications may 65 be made in the same without departing from the spirit of my invention; hence, I do not wish to be understood as limiting myself to the exact

form, construction, arrangement and combination of parts herein shown and described or uses mentioned.

What I claim as new and desire to secure by Letters Patent is:

1. In a device of the kind described, a push button switch, means comprising a bent shaft supported thereon for controlling the switch, said controlling means being adapted for movement around said switch to bring the bent portion of the shaft opposite either push button of the switch means to thereby turn the same on or off, and said controlling means adapted for association with means for timing the control thereof. 80
2. In a device of the kind described, a push button switch, means comprising a bent shaft supported on said switch for controlling its operation, a roller arranged on the bent portion of said shaft, said shaft means adapted for bodily movement around said switch to bring the roller on the same opposite either push button to thereby turn the switch on or off, and said shaft means being adapted for threadable association with means for timing the control thereof. 85
3. In a device of the kind described, a socket having a switch associated therewith, movable means carried by said socket and rotatable therearound for controlling the operation of the switch, and adapted for connection with means for timing the control thereof, said timing means having a key therefor and said controlling means adapted to receive said key from said timing means. 90
4. In a device of the kind described, a socket having switch means associated therewith, a support transversely arranged on said socket, and means transversely supported on said support for controlling the switch means, said support and controlling means adapted for bodily movement on said socket whereby the controlling means may be brought into various positions to operate said switch means, and said controlling means adapted for detachable connection with means for timing the control thereof. 100
5. In a device of the kind described, a socket having a head and a body part with switch means arranged therein, a band secured to said head, a support secured to said band, means for controlling the switch means mounted in said support, and said band, support, and controlling means adapted for bodily movement around said socket whereby said controlling means may be brought into various positions to thereby act upon said switch means in the desired manner to turn the same on or off, and said controlling means adapted for detachable association with an alarm winding stem of a clock for actuating and timing said controlling means. 110
6. In a device of the kind described, a socket having switch means associated therewith, means supported on said socket for controlling the switch means, said controlling means adapted for bodily movement on said socket and around it whereby the controlling means may be brought into positions for acting upon said switch means and in neutral positions whereby said switch means may be manually operated, and said controlling means adapted for detachable connection with means for timing the control thereof. 120
